CLAIM

The ornamental design for a casino game and chair set, as shown and described.

DESCRIPTION

FIG. 1 is a perspective top front right view of a casino game and chair set, including a casino game and a chair, showing my new design;

FIG. 2 is a perspective top rear left view thereof;

FIG. 3 is a front elevation view thereof;

FIG. 4 is a rear elevation view thereof;

FIG. 5 is a left elevation view thereof;

FIG. 6 is a right elevation view thereof;

FIG. 7 is a top plan view thereof; and,

FIG. 8 is a bottom plan view thereof.

The claim is directed to the collective appearance of the casino game and chair set shown in FIGS. 1-8. The components of the set are arranged on the drawing sheet for the convenience of illustration, and the relative positioning of the casino game and chair forms no part of the claimed design.
